ATTORNEYS

UNITED STATES PATENT OFFICE.

EDWARD L. NERTNEY, OF NORTH SIDE COHOES, NEW YORK.

BALL-GAME APPARATUS.

Application filed March 28, 1928. Serial No. 265,426.

This invention relates to game apparatus and has for its primary object to provide mechanism by means of which a game in simulation of a regular baseball game may be played indoors on a table or the like, and in which all of the rules as to playing the regular game, scoring, etc., may be observed.

A further object of the invention resides in so constructing and designing the apparatus that it may be manufactured and placed on the market at a relatively low cost.

Another object of the invention consists in the construction of such a device which is adaptable to both left-handed batters as well as right-handed batters, thereby more closely simulating the actions as practiced on the regular baseball diamond.

Other objects and advantages of the invention will be apparent from the following description when taken in connection with the accompanying drawing; in which

Figure 1 is a plan view of the apparatus with the cover removed.

Figure 2 is a vertical section taken on line 2-2 of Figure 1; and

Figure 3 is a perspective view partly broken away of the return track or runway for the ball.

Referring to the drawing more specifically the numeral 1 indicates a tray such as the lower section of the ordinary box of the slip cover type and is provided with side walls 2 and end walls 3. Mounted within the tray 1 is a platform 4 provided with down-turned side flanges 5 and down-turned end flanges 6. These flanges 5 and 6 form legs or supports for the platform 4 and space the latter above the bottom of the tray 1. This platform is of a width equal to that of the interior of the tray but is of somewhat shorter length so that when mounted in the tray as indicated in Figure 1 one of its ends will be spaced from the adjacent end of the tray so as to provide a compartment 7. The platform 4 may be glued or otherwise secured within the tray 1 and has outlined on its upper surface the diagram of a baseball field as indicated by numeral 8. On the field as thus outlined is

provided a plurality of apertures 9, all of which are provided with indicia such as "Home run", "Three base hit", "Fly out", "Bunt safe", "Error", "One base", etc.

The apertures 8 are of a diameter to permit the passage of a ball 9 which is employed as a baseball in the operation of the game as disclosed herein. A baseball bat 10 is provided for use in conjunction with the ball 9 in a manner which will be readily understood and this bat is provided with a pivot pin 11 by means of which it may be pivoted in either of the apertures 12 disposed on opposite sides of the home plate 13. By this means it will be apparent that the bat may be used by either a right-handed or left-handed batter, thereby closely simulating the actions of an ordinary baseball game played out-of-doors.

The ball being struck by the bat 9, is projected across the playing field and will ordinarily pass through one of the apertures 9 which, by its indicia, will indicate whether the play is to be counted as a single, two-base hit, an out, or the like.

It is desirable, of course, that some means be provided for returning the ball to the compartment 7 in order that it may be available for further use. To this end I provide a runway which is indicated generally by the numeral 14. This runway comprises a sheet of cardboard folded intermediate its ends to provide a continuous base portion 15, side walls 16, and flaps 17 which are joined together as indicated by numeral 18 to provide the upper wall 19 of the runway. At one end of the runway intermediate the top and bottom walls 17-15, is placed a spacer block 20 and at its opposite ends the upper and lower walls are held in substantial contact mid-way of the sides of the runway by a strip of paper or the like adhesively secured to these members as indicated by numeral 21. It will thus be seen that in the finished runway the flaps 17 incline downwardly toward the longitudinal center of the runway and also incline downwardly from the end to which has been applied the spacer 20.

This runway is mounted in the tray 1 prior to the insertion therein of the platform 4 and is spaced from both ends of the tray 1. The runway is preferably adhesively secured in the tray with its downwardly inclined end in contact with the adjacent flange 6 of the platform 4 and in order that a ball may be returned to the compartment 7 the flange 6 is provided with a notch 6'; 5 likewise the partition 22 which cooperates with the walls of the box to provide the compartment 7 is provided with an opening 23 which registers with the opening 6' in the flange 6. The opposite end of the runway 10 14 is located just in front of the home plate 13 and in order to space the top of the runway a sufficient distance below the platform 4 so as to allow a ball to travel along the platform, I provide a spacing strip 24 which 15 is adhesively secured to the top of the runway at its end which is located adjacent the home plate. This strip 24 also serves the further purpose of preventing a ball from traveling rearwardly so as to get in back of 20 the runway and thus be prevented from returning to the compartment 7.

The entire device, with the exception of the bat and ball is made of paper and cardboard and is so designed as to permit of its 30 construction at a very low cost due to the fact that very few operations are required in constructing the platform or playing surface and the runway which is disposed below the same.

35 Preferably, the entire device when not in use is inclosed by a cover of the slip type as indicated in dotted outline in Figures 1 and 2.

In the operation of the device, two sets of 40 cardboard chips or the like, nine in number, are provided; the two sets being of different colors, for instance, one set being red and the other set blue. The game is played by two persons, one selecting the blue chips and one 45 the red. The player representing the team in the field rolls the ball towards the home plate 13 and the player representing the team at bat, having placed the bat in the proper pivot aperture 12 depending upon 50 whether he is a right or left-handed player, swings the bat, provided the ball is over the plate, and drives it across the platform 4. The ball will enter one of the apertures 9 and by the indicia adjacent the aperture the 55 play will be determined, as will be obvious. The ball, after passing through the aperture 9 will travel down the inclined runway 14 and pass into the compartment 7 where it is again ready for use. The regular rules 60 as employed with the outside game of baseball will prevail in the present simulated game of baseball, and a detailed description of the manner in which fouls are counted, etc., is believed to be unnecessary.

65 From the foregoing description taken in

connection with the accompanying drawing it will be apparent that I have devised a baseball game apparatus to be played indoors and in which all of the rules of the ordinary outside ball game may be observed; 70 that the device is simple and inexpensive in construction; and that it is so designed as to permit its use by either right-handed or left-handed players, just as in the ordinary game of baseball. 75

In accordance with the patent statutes I have described what I now believe to be the best embodiment of the invention, but I do not wish to be understood thereby as limiting myself or the scope of the invention as 80 many changes and modifications may be made without departing from the spirit of the invention; all such I aim to include in the scope of the appended claims.

What I claim as new and desire to secure 85 by Letters Patent is:

1. A device of the class described including a tray, a platform mounted in said tray and including downturned ends and sides resting on the bottom of said tray, one end 90 of said platform being spaced from the adjacent end of the tray to provide a compartment, one downturned end of said platform forming a wall of said compartment and provided with an opening at its lower edge, 95 and a runway below said platform and inclined toward the opening in said wall.

2. A device of the class described including a tray, a platform mounted in said tray above the bottom thereof and spaced from 100 one end of the tray to form a compartment, a wall extending transversely of said tray and forming a support for the end of the platform adjacent said compartment, a 105 cardboard runway substantially co-extensive with said platform and mounted below the same, said wall being provided with a notch to permit the passage of a ball from the runway to the compartment.

3. A ball game apparatus, a runway including a sheet of cardboard folded to provide spaced upper and lower walls, a spacer block between said walls at one end of the runway, and means holding said walls in substantial contact at the other end of the 115 runway.

4. In a device of the class described, a runway including a sheet of cardboard folded intermediate its ends to provide a continuous bottom wall and side walls, the 120 free ends of said sheet being brought together adjacent the middle of the trackway to form a top wall, means for holding said upper and lower walls spaced apart at one end of the runway, and means for attaching 125 the ends of the cardboard sheet to the bottom wall at the opposite end of the runway.

5. A device of the class described, including a tray, a platform mounted in said tray above the bottom thereof and spaced from 130

one end of the tray to form a compartment, a wall extending transversely of said tray and forming a support for the end of the platform adjacent said compartment, a cardboard runway of substantially the width of said tray mounted below said platform and spaced from the ends of said tray, said wall

being provided with a notch to permit the passage of a ball from the runway to the compartment, and a cardboard strip secured 10 across the opposite end of said runway to serve as a spacer between said platform and runway.

EDWARD L. NERTNEY.
